EXTRUSION PRESS

Ernst Muller, Duisburg, Germany, assignor to Hydraulik
G.m.b.H., Duisburg, Germany
Filed June 22, 1962, Ser. No. 204,378
4 Claims. (Cl. 72—265)

The present invention relates to an extrusion press for producing hollow or tubular members and more particularly to a hydraulic press of this type in which the driving cylinder for the piercing mandrel is located outside the main pressure cylinder and is rigidly connected to the piston of this cylinder.

Hydraulic metal tube presses are already known in which the driving cylinder providing the driving of the piercing mandrel is disposed axially behind the main cylinder and is rigidly connected to the press frame. In such arrangements the mandrel drive depends on the movement of the main pressure ram. In a metal tube press of that type the mandrel stroke must be of such a length that it is capable of carrying out the stroke of the pressure ram as well as of the additional stroke for piercing the block. For this reason, the mandrel drive cylinders and return mechanisms must be made of a corresponding size and therefore these presses have substantial dimensions either in length or in height.

In other prior art presses of this type, the mandrel drive has been mounted in such a manner in the main pressure piston that it serves simultaneously as cylinder for the mandrel drive piston or so that it may receive this piston within its structure. This known arrangement has the disadvantage that the driving assembly, including the return mechanism for the mandrel, are not easily accessible, which is very undesirable in the event of a disturbance or a breakdown of the mechanism, or when parts thereof are to be exchanged.

In a tube press of this construction a guiding arrangement is usually required for the mandrel rod and it is generally located in front of the main pressure cylinder. This mandrel guide takes up a substantial amount of space and due to its length requires a substantial interval between the cylinder and the crossbeam in order to provide still enough room to insert the metal blocks. This necessitates very long frame columns or a frame structure of great length which leads to greater dimensions of the frame construction and thus also to a considerable increase in the weight of the structure. This prior art arrangement does not provide the desired reduction in the construction length and the substantial decrease of the weight of such a press.

It is therefore an object of the present invention to provide a metal tube press having a driving means which is mounted axially behind the main pressure cylinder and which is independent of the main pressure piston, presenting the advantage of a clear unencumbered construction and easy accessibility of the driving elements combined with the additional advantage of avoiding the long strokes for the driving cylinder of the mandrel and the return mechanism of the prior art construction, whereby a substantial reduction of size and weight of the press is obtained.

According to the invention the driving cylinder for producing the actuation of the mandrel is mounted for movement outside the main pressure cylinder and is rigidly connected to the main pressure piston. By means of this connection the stroke distance of the driving piston for the piercing mandrel may be limited to the extent necessary for the piercing stroke because its driving cylinder carries out all the movements of the main pressure ram fixed to the main pressure piston. At the same time this novel construction provides an additional advantage in that the driving elements for producing the movement of the pierc-

2

ing mandrel which are located behind the main pressure piston are made freely accessible from all sides so that in the event of disturbances or of a breakdown, or for exchanging parts, no difficult or time-consuming repair work will be necessary.

According to a main feature of the invention the connection between the driving cylinder for producing the movement of the piercing mandrel and the main pressure piston consists of an extension of the main pressure piston passing rearwardly through the main pressure cylinder. This extension serves simultaneously as a guide for the mandrel rod and is connected preferably over a plurality of columns to the driving cylinder of the mandrel. In this case the arrangement is preferably so designed that the extension of the main pressure piston terminates in a crossbeam which is connected through columns to a crosshead which carries the mandrel driving cylinder. By means of the column construction between the crossbeam and the crosshead, the free accessibility of the mandrel drive is realized in a particularly advantageous manner. A further advantage of the invention resides in the fact that due to the constructionally clear arrangement between the main drive and the mandrel drive during the extrusion of solid bars instead of tubes, the portion of the mandrel drive may be easily uncoupled and need thus not always be carried along by the main pressure piston.

Further objects and advantages of the present invention will become apparent from the following description taken in combination with the attached drawing in which the single figure shows in longitudinal sectional elevation a press for the extrusion of a tubular member according to the invention.

Referring now to the drawing, the main pressure cylinder 1 is open at one end and is connected by means of columns or other frame elements 2 of the press to an abutment block 3 which has a central extrusion opening 3a. A die 4 is set partly into the inner face of the abutment block 3 and communicates with the extrusion opening 3a of the abutment block. A billet container 5 is mounted inwardly of the die 4, its bore 5a communicating and being aligned with the opening of the die and with the extrusion opening 3a. As shown in the drawing, a metal block or billet 6 to be pierced and extruded is located in front of the bore 5a of the billet container 5. The main pressure piston 8 is hollow and has a hollow extension at one end which constitutes a ram 7 for engaging the billet and for extruding it through the die. As shown in the drawing, ram 7 is located in its extreme end position to the left, the main pressure piston 8 having moved as far as possible into cylinder 1. The main pressure piston has a tubular extension 8a at the other end which passes in sliding engagement through a central opening provided for that purpose in the end wall 1a of main pressure cylinder 1. The extension 8a terminates in a transverse plate or crossbeam 8b which is connected by means of columns 9 to a crosshead 10. This crosshead 10 has a cylindrical rearward extension which constitutes a driving cylinder 11 in which a driving piston 12 is received which is adapted to actuate the piercing mandrel 14. In the particular arrangement shown, the driving cylinder 11 for the piercing mandrel carries out all the movements of the main pressure piston.

The driving cylinder 11 is shown as an integral part of the crosshead 10, but it is understood that it may be a separate member which is fixed in any suitable manner to the crosshead. The driving piston 12 terminates in a disc or head 12b of larger diameter than the piston body or shaft, the head portion of the piston being in sliding engagement with the inner wall of cylinder 11. The piston head may thus be employed to return the piston into the starting position. The driving piston 12 is connected

over the mandrel rod 13 passing through the hollow center of the main pressure piston to the piercing mandrel 14 which extends partly through the center of the main pressure piston and partly through the center of the ram 7 which is shown as being integral with the main pressure piston. The piston extension 8a serves as a guide for the mandrel rod 13.

The crosspiece 12a of driving piston 12 is provided with adjustable stops 17 which are adapted to pass through suitable bores 15 in the crossbeam 8b and strike corresponding buffers 16 fixed to the end wall of the main pressure cylinder 1. These stops 17 serve to set the position of the mandrel in the die 4 when the pressing operation is carried out while the mandrel is stationary.

In operation, assuming the pistons 12 and 8 to be in their extreme end positions in which the ram 7 and the mandrel 14 are withdrawn from the receiver 5, a metal block 6 is inserted into the receiver 5 in the customary manner. Pressure medium is introduced into the cylinder 11 behind the piston head 12b through a pipe or other suitable conduit 18 connected to the end of this cylinder as shown in dotted lines. The pressure medium causes the piston 12 to move to the right thereby forcing the mandrel 14 into the metal block to pierce a hole therethrough. The forward movement of the piston 12 and mandrel 14 is continued until the front end of the mandrel projects into the opening of the die 4. The stops 17 are so adjusted as to strike against the buffers 16 in this position of the mandrel thereby preventing further forward movement thereof. Pressure medium is then introduced to the left side of the piston 8 in the main cylinder 1 and the main piston with the ram 7 is moved towards the right as shown in the drawing. During its forward movement the ram of the main piston will force the metal block 6 through the die opening past the mandrel to thus produce a tubular member.

The return of the main pressure piston and of the mandrel piston may be effected by any suitable conventional arrangement (not shown) for example by introducing pressure medium in front of the mandrel piston head and by providing pull-back cylinders and pistons on opposite sides of the main pressure piston.

What is claimed is:

1. A press for extruding tubular members comprising in combination an abutment block having an extrusion opening therein, an extrusion die supported adjacent the inner face of said abutment block, a billet container mounted adjacent said extrusion die and having a bore communicating with said die and said extrusion opening, a stationary pressure cylinder mounted in spaced relation

to said billet container and rigidly connected to said abutment block, said stationary pressure cylinder having an open end facing said billet container and a remote end having an opening therethrough, a first hollow piston slideably received in said stationary pressure cylinder, a hollow ram at one end of said first piston and adapted to slide in the bore of said billet container, a tubular extension at the other end of said first piston and slideable in the opening in said remote end of said stationary cylinder, a crossbeam fixed to the end of said tubular extension, a crosshead rigidly connected in spaced relation to said crossbeam, a movable pressure cylinder rigidly connected to said crosshead, a second piston slideably received in said movable cylinder, a crosspiece fixed to said second piston and disposed for movement between said crossbeam and said crosshead, means on said crosspiece for adjusting the stroke of said second piston, a rod connected to said second piston and slideably received in said tubular extension, and a piercing mandrel connected to said rod and slideably received in said first piston and in said hollow ram, said first piston being operable independently of said second piston to move said mandrel relative to said hollow ram into said billet container and said die.

2. A press for extruding tubular members as defined in claim 1 wherein said means for adjusting the stroke of said second piston consist of axially extending elongate adjustable stops.

3. A press for extruding tubular members as defined in claim 1 wherein buffer means are fixed to said remote end of said stationary pressure cylinder opposite said crossbeam, said crossbeam having openings aligned with said buffer means and with said elongate adjustable stops, said elongate adjustable stops being adapted to pass through said openings to engage said buffer means.

4. A press for extruding tubular members as defined in claim 1 wherein said crosshead is connected to said crossbeam by a plurality of spaced connecting columns.
